UNITED STATES PATENT OFFICE.

CLEN S. HUMPHREY, OF BROOKLYN, NEW YORK.

DESIGN FOR A POWDER CONTAINER.

60,190.

Specification for Design.

Patented Jan. 10, 1922.

Application filed October 10, 1921. Serial No. 506,880. Term of patent 7 years.

To all whom it may concern:

Be it known that I, CLEN S. HUMPHREY, a citizen of the United States, a resident of the city of New York, borough of Brooklyn, in the county of Kings and State of New York, have invented a new, original, and ornamental Design for a Powder Container, of which the following is a specification.

Reference being had to the accompanying drawing, forming part thereof in which;

Figure 1 is a front elevation of the container.

Figure 2 is a side view thereof.

Figure 3 is a plan view of the same; and Figure 4 is a horizontal sectional view taken on the line 4—4 of Figure 1.

I claim:

The ornamental design for a powder container, substantially as shown.

CLEN S. HUMPHREY.
